UNITED STATES PATENT OFFICE.

MATHEW ANGUS SMITH, OF CLARENDON HILLS, MASSACHUSETTS, ASSIGNOR
TO THE WARWICK CYCLE MANUFACTURING COMPANY, OF SPRINGFIELD,
MASSACHUSETTS.

MANUFACTURE OF RIMS FOR BICYCLE-WHEELS.

SPECIFICATION forming part of Letters Patent No. 557,520, dated March 31, 1896.

Application filed March 30, 1894. Serial No. 505,687. (No model.)

To all whom it may concern:

Be it known that I, MATHEW ANGUS SMITH, a subject of the Queen of Great Britain, residing at Clarendon Hills, in the county of 5 Norfolk and State of Massachusetts, have invented new and useful Improvements in the Manufacture of Rims for Bicycle-Wheels, of which the following is a specification.

This invention relates to the manufacture 10 of bicycle-wheel rims, more particularly to the method and means employed for laying together and holding in place and imparting pressure to the strips or layers of wood from which the rim is composed.

Reference is to be had to the accompanying 15 drawings, in which—

Figure 1 is a plan view of the novel apparatus employed, showing also the action thereof upon the layers of wood from which the 20 rim is produced. Fig. 2 is a vertical sectional view of the same, taken on line 2 2, Fig. 1. Fig. 3 is a perspective view of one of the segments, a plurality of which form the pressure device for internal application upon the 25 layers of wood under process of formation.

Fig. 4 is a perspective view showing a portion 30 of the rim as built up by the employment of the present improvements, while Fig. 5 is a similar view showing the rim as further formed to adapt it for a pneumatic-tired wheel.

I have discovered that in making up wood rims for bicycle-wheels from layers of thin stuff which are superimposed and glued together and bent around to annular form and subjected to pressure until the wheel has become set that by merely holding the rim at its external periphery against distortion or any irregular or uneven displacement and im- 35 parting the pressure upon the built-up rim from its inside that the strength and stiffness or stability of the rim is increased in a remarkable degree beyond that found in a built-up wheel pressed from the outside; and there- 40 fore my invention, in part, resides in the method of producing a stiff built-up wood rim, which consists in bending around annularly and uniting one layer or strip of the wood upon another and subjecting the so-united 45 layers to an expanding pressure while the ad-

hesive which unites the layers is becoming set; and the invention furthermore consists in an apparatus or mechanism for carrying out the process, and all as will hereinafter fully appear, and be set forth in the claim. 55

Referring to said drawings, A represents a table or bench, on which is placed a sheet *a* of zinc or other metal, while resting upon said zinc is a cast-iron ring *B*, having a smooth inner periphery, while in its base is a comparatively wide annular groove *b*. A steam-heating pipe *d*, circularly arranged, rests upon the zinc and within the chamber comprised in said annular groove, it having suitable ingress and egress pipes coupled thereto for 60 permitting, properly, the steam circulation to suitably heat the ring. The ring is internally of the same size as the rim is to be externally. Within the ring are a series of cast-iron segments *D*, here shown as quadrants, and which 65 are shown as comprising rim-segments and hub-segments united by suitable spokes or arms and strengthening-ribs, preferably thus in lieu of a more solid formation for lightness and facility of handling, and these, 70 when assembled with their radial edges in contact, as seen in Fig. 1, have a diameter so much less than the internal diameter of the ring *B* as approximately equals the thickness of the rim to be produced. The segments 75 have their inner corners concave, as seen at *f*, to conduce to the formation of a small circular wall concentric with the external periphery, which circular wall is downwardly tapering for the reception of the expanding 80 cone *G*, which has below it the screw-shank *g*, which screw engages in the screw-tapped metallic bushing *h* set in the bench or table, while above this cone is a cross-head *i* to afford adequate means for turning the actuating-screw of the cone. 85

It will be noticed that one of the segments has at its outer edge three depressions or notches *m m m*.

Now in making up a rim the workmen first 95 take a strip with scarf'd ends and of sufficient length and gluing it on its inner face bend it around and place it with its outer face against the inner face of the ring *B*, the ends making a scarf-joint. The next layer, of 100

slightly decreased length, is glued and bent around and laid closely within the first layer, its scarf-joint coming at a point a little way around from the joint of the first layer, and 5 the third layer is similarly applied within the second. More than three layers may be used, if desired. The segments are next brought into effect by forcing them outwardly through means of the expanding cone, the segment 10 having the said depressions *m m m* being so placed that the depressions come respectively next to or opposite the scarf-joints. The pressure of the segments outwardly having been effected in the maximum degree, wedges 15 or paired wedges, as seen at *n*, are driven between the base of the depressions *m* and the wood rim to impart a special pressure upon the scarf-joints to assure the integrity of the rim structure thereat.

Having thus described my invention, what 20 I claim, and desire to secure by Letters Patent, is—

In an apparatus for making built-up wood wheel-rims, a rigid annular die for the reception of the rim and a plurality of segment- 25 shaped parts of less diameter than the interior diameter of the rim, and lying within said die, and means for forcibly expanding said segments against the inner periphery of said rim, and means for applying an excess of 30 pressure at one or more points on the periphery of one or more of said segments, substantially as described.

M. ANGUS SMITH.
